Harvey Brody, Los Angeles, Calif., assignor to Norvey,
Inc., Los Angeles, Calif., a corporation of California

Filed Apr. 8, 1963, Ser. No. 74,339

Term of patent 14 years

(Cl. D58—26)

FIG. 1.

FIG. 2.

FIG. 4.

FIG. 3.

FIG. 5.

FIG. 1 is a side elevational view of a dispenser cap and spout for liquids embodying my new design, with the spout in retracted position and the end closure in place; FIG. 2 is a top plan view of the same;

FIG. 3 is a front elevational view of the same with the spout in open position and the end closure removed;

FIG. 4 is a side elevational view of the same with the spout in open position and the end closure removed;

FIG. 5 is a top plan view of the same with the spout in open position and the end closure removed.

The bottle shown in broken lines is for illustrative purposes only.

The characteristic feature of my design resides in the curved configuration of the spout in its extended position.

I claim:

The ornamental design for a dispenser cap and spout for liquids, substantially as shown and described.
